CLAIM

The ornamental design for an agricultural tool as shown and described.

DESCRIPTION

FIG. 1 is a front perspective view, with environment, of the agricultural tool showing a first embodiment of the new design;

FIG. 2 is a front perspective view thereof;

FIG. 3 is a rear perspective view thereof;

FIG. 4 is a front view thereof;

FIG. 5 is a back view thereof;

FIG. 6 is right side view thereof;

FIG. 7 is a left side view thereof;

FIG. 8 is a top view thereof; and,

FIG. 9 is a bottom view thereof.

The broken line showing of the straps in FIG. 1 is included for the purpose of illustrating environmental portions only of the agricultural tool and forms no part of the claimed design.

1 Claim, 7 Drawing Sheets
